(57) **CLAIM**

The ornamental design for an ornamental secondary beverage carton, as shown and described.

DESCRIPTION

FIG. 1 is a top perspective view of an ornamental secondary beverage carton, showing our new design;

FIG. 2 is a bottom plan view thereof;

FIG. 3 is a front elevation view thereof;

FIG. 4 is a rear elevation view thereof;

FIG. 5 is a right side elevation view thereof, on an enlarged scale;

FIG. 6 is a left side elevation view thereof, on an enlarged scale;

FIG. 7 is a front, top perspective view thereof; and,

FIG. 8 is a top plan view thereof in an unfolded condition. In the drawing, the dash lines represent the cut lines, and the dash-dot lines represent the fold lines.
